UNITED STATES PATENT OFFICE.

ANDREW WUEST, OF CLEAN, NEW YORK.

VENTILATOR-DAMPER.

1,219,615.

Specification of Letters Patent. Patented Mar. 20, 1917.

Application filed March 1, 1916. Serial No. 81,456.

To all whom it may concern:

Be it known that I, ANDREW WUEST, a citizen of the United States, residing at Olean, in the county of Cattaraugus and

60

5 State of New York, have invented a new and useful Ventilator-Damper, of which the following is a specification.

This invention relates to dampers particularly designed for use in connection with 10 ventilators.

One of the objects of the invention is to provide a damper designed to fit properly within the ventilator below the cap and which, when rotated in one direction will 15 move upwardly to close the annular opening between the cap and the ventilator body thereunder.

A further object is to provide novel means whereby the damper will be caused to move 20 upwardly when revolved in one direction and, when released, will gravitate back to its normal position.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed can be made within the scope of what is claimed, without departing from the spirit of the invention.

In the accompanying drawings the preferred form of the invention has been shown.

35 In said drawings:—

Figure 1 is a central vertical section through the ventilator and showing the damper in its normal or lowermost position.

Fig. 2 is a similar view showing the 40 damper raised to close the ventilator.

Fig. 3 is a bottom plan view of the ventilator and damper.

Fig. 4 is a perspective view of the damper.

Referring to the figures by characters of 45 reference 1 designates the cylindrical body of the ventilator provided at its upper end with an annular flange 2 and with upwardly extending angular brackets 3 supporting a conical cap 4. This cap extends entirely 50 over the upper end of the ventilator and is preferably of approximately the same diameter as the flange 2. Brackets 3 project radially beyond the cap and serve to connect a guard ring 5 to the ventilator, this ring being concentric with but spaced from the 55 cap and flange.

The parts heretofore described are of an ordinary type of ventilator and, in themselves, constitute no part of the present invention.

Secured within the body 1 are substantially U-shaped guide brackets 6 each of which has a grooved anti-friction roller 7 journaled therein. The upper ends of each bracket are inturned to form retaining lips 65 as shown at 8.

Mounted for rotation within the body 1 is a cylindrical damper 9. This damper has its lower end portion provided with angular recesses whereby substantially triangular 70 wings 10 are formed. Each of these wings has a bead 11 along one of its edges and these beads are adapted to work within the respective brackets 6 so as to ride upon the anti-friction rollers 7 and be held thereto by 75 the inturned lips 8. Thus it will be seen that when the damper is rotated in one direction, the beads will travel along the rollers and cause the damper to move upwardly to position its upper edge against the cap 4 and 80 thus completely close the ventilator. This position of the damper has been illustrated in Fig. 2.

In order to reduce lateral sway of the damper within the ventilator casing to the 85 minimum, a rib 12 is pressed outwardly from said damper and is adapted to work close to and if necessary engage the inner surface of the ventilator. This spacing rib is preferably extended approximately parallel 90 with the edges of the wings.

The damper is braced transversely by a plurality of crossed radial brace rods 13 connected at their centers as shown at 14 or can be braced in any other manner desired.

95

Attached to the ventilator casing at a suitable point therein is a bracket 15 to which is connected a swinging arm 14 carrying a pulley 17. Mounted on this pulley is a flexible actuating element preferably in 100 the form of a chain 18 although it is to be understood that a knotted cord or any other suitable device may be used. This flexible element is attached at one end to the lower end portion of one of the wings 10 and its other end may hang freely within convenient grasp of the operator. The depending portion of the flexible actuating element 18 is preferably extended through a holding bracket 19 having a keyhole slot 20.

105

One of the wings 10 can be cut away to form an angular recess 21 as shown in Figs.

110

1 and 2, one wall of this angular recess being designed to come against one side of the bracket 15 when the damper is in lowered position thus to limit the downward movement of the damper. This will be obvious by referring to Fig. 1.

Assuming that the damper is in the lowered or open position of Fig. 1, the same can be raised to closed position simply by 10 pulling downwardly on the flexible actuating element 18. This element will pull inwardly on the wing 10 to which it is attached and will cause the damper 9 to rotate. As the beaded edges 11 of the wings 15 10 are guided within the bracket 6 it will be obvious that such rotation of the damper will result in its upward movement until the upper end thereof comes against cap 4. The damper can be held in this raised position 20 by shifting the connection 18 into the narrow portion of the slot 20 whereupon it will be engaged and held. By removing the connection 18 from the narrow portion of the slot and releasing said connection the damper will be free to turn downwardly to its initial position.

What is claimed is:—

1. The combination with a cylindrical 30 ventilator and a cap extending thereover and spaced therefrom, a cylindrical damper fitted within the ventilator, said damper having depending wings with inclined edges, means mounted within the ventilator for engaging and guiding said edges, and means

for rotating the damper, said guiding means 35 coöperating with the edges of the wings to shift the damper longitudinally during such rotation.

2. The combination with a cylindrical 40 ventilator body and a cap extending thereover and spaced therefrom, of a cylindrical damper mounted to rotate and to shift longitudinally within the body, said damper having depending wings provided with inclined lower edges, damper supports 45 movably engaged by said edges, and means located within the damper for rotating said damper to shift it longitudinally toward the cap.

3. The combination with a cylindrical 50 ventilator body and a cap extending thereover and spaced therefrom, of a cylindrical damper mounted to slide and rotate within the body and having depending wings provided with inclined lower edges, damper supports 55 secured within the body and engaging said edges, and means secured to and surrounded by the damper for rotating said damper relative to its supports thereby to shift the damper longitudinally within the 60 body and toward the cap.

In testimony that I claim the foregoing as my own, I have hereto affixed my signature in the presence of two witnesses.

ANDREW WUEST.
